UNITED STATES PATENT OFFICE.

ALEXANDER McNAB, OF BRIDGEPORT, CONNECTICUT.

POWER-OPERATING MEANS FOR RUDDERS.

Application filed May 9, 1924. Serial No. 712,075.

To all whom it may concern:

Be it known that I, ALEXANDER MCNAE, a subject of the King of Great Britain, residing at Bridgeport, State of Connecticut, have invented certain new and useful Improvements in Power-Operating Means for Rudders, of which the following is a specification.

This invention relates to the maneuvering gear of ships or boats and has particular reference to gear of this kind in which the rudder is formed of two substantially curved blades mounted behind the propeller in such a way that they may be varied from parallelism to a mutually inclined position in which substantially no water is allowed to pass between the blades, this form of rudder maneuvering gear is fully described in U. S. Patent No. 1,186,210.

The form of maneuvering gear referred to has been found in practice to give very much improved maneuvering qualities to the vessel and to be particularly valuable in cases where it is undesirable to vary the speed of the engine as in motor driven vessels, all maneuvering such as turning in a narrow compass or reversing being carried out entirely by the rudder setting. In addition, the quicker stopping of the vessel which can be obtained from the use of the rudder is a very great advantage. Many further advantages will be obvious to those familiar with the navigation of ships or boats.

In view of the advantages obtained by the use of this rudder maneuvering means it has been fitted to a very large number of vessels. Hitherto the rudder setting has been manually controlled but it has been found in practice that whereas manual control is entirely satisfactory in small vessels it is desirable to fit power means of control for the maneuvering gear in the case of larger vessels and this invention specifically relates to such power control means.

It is an object of the invention to provide a power operated control means for maneuvering gear of the kind described which can be controlled from a point adjacent the steering wheel.

It is a further object of the invention to provide an electrical power operating means for maneuvering gear of the kind described.

It is a still further object of the invention to provide brake mechanism to ensure

that the movement of the mechanism is arrested at the desired instant.

It is a still further object of the invention to provide automatic means to limit the movement of the rudder blades.

It is a still further object of the invention to provide a power driven rudder control in which while the necessary manipulation has been reduced to great simplicity, a thoroughly reliable apparatus is provided capable of all required adjustments.

It is a still further object of the invention to so arrange the apparatus as to form a compact structure mountable in a small space in the most convenient position as for instance directly over the rudder.

It is a still further object of the invention to provide means whereby should any obstruction prevent movement of the rudder blades, injury to the blades will be avoided by preventing the further application of power thereto until so desired.

It is a still further object of the invention to provide gearing to decrease the speed of operation of the rudder blades while increasing the power communicated thereto.

Further objects of the invention will hereinafter appear and be specifically pointed out in the appended claims.

In the accompanying drawings, which are intended to illustrate a preferred embodiment of the invention but which are not regarded as in any way limiting the invention the scope of which is defined in the appended claims, the preferred embodiment of my invention is shown as applied to controlling means in which the movement of the blades is effected by the displacement of a member on a threaded spindle, such as described in U. S. Patent No. 1,371,492, but the particular arrangement of means effecting the movement of the blades forms no part of this invention which relates to power driven means for operating same.

As above stated the particular form of rudder to which this invention relates forms the subject matter of a U. S. patent and therefore only sufficient description of the operation thereof will be here given to enable a clear understanding of the invention to be obtained.

Fig. 1 is a side elevation of a complete power unit mounted on a common base plate adapted to be mounted adjacent the rudder.

Fig. 2 is a front elevation of the unit

shown in Fig. 1, showing the solenoid brake arrangement.

Fig. 3 shows a convenient arrangement of the control means in the wheel house, push buttons controlling the necessary switches being arranged in a box mounted on the binnacle.

Fig. 4 is a detail view of the limit switch arrangement of the unit shown in Fig. 1.

Fig. 5 is a plan view of the control engine and rudder gear showing the relation of the unit shown in Fig. 1 to the rudder control.

Fig. 6 is a diagrammatic representation of as much of the electrical circuits of the power unit as is necessary in order to comprehend the manner in which the functioning of the mechanism is controlled, the setting of the switches being that for ahead maneuvering.

The rudder referred to and known in the marine engineering art as the Kitchen maneuvering and reversing rudder consists essentially of two blades 11, 12 each substantially semicircular in vertical section and pivoted together vertically preferably so as to surround the propeller. The blades are so shaped along the rear vertical edge that they may be brought into contact throughout the length of said rear edge, their inner faces then being substantially at right angles and preventing the passage of any water therebetween.

One of the blades or deflectors is operated by a solid shaft "A" and the other by a hollow shaft "7" concentric with the solid shaft. By suitable mechanism the deflectors or rudders are made to turn together in the same direction or equally in opposite directions.

To be as effective as possible the rudder should be placed in, or near, the propeller race. This ensures that the speed of the water passing over the rudder will be greater than the speed of the vessel through the water by a varying value which may be as much as 30 per cent; and that in starting the ship from rest there will be a flow of water over the rudder, giving steering power before the vessel has much weight on. This is effected in the most efficient way possible, since not only are the blades in the propeller race but confine the race adjacent the propeller.

Variation of speed.—For ordinary direct full speed ahead the rudder will be opened until nearly parallel, being slightly less at the after end. When the deflectors are partially closed, the speed of the boat will be reduced to about one-half the full ahead speed, the engines still running at the same revolutions. When the rudders are closed still further the boat will remain stationary. In this case the forward thrust on the propeller is balanced by an equal astern thrust on the rudders. When the deflectors are

closed together, the reaction on the rudders causes the vessel to go astern. This position gives the maximum astern speed.

Steering.—The vessel can be steered by carrying helm on the rudders, whether they be fully open, partially closed or quite closed. It has been found that 25 degrees to 30 degrees of helm is quite sufficient for all practical purposes, although with ordinary rudders as much as 38 degrees or even 40 degrees of helm is used. This limitation of helm angle tends to decrease of size in the steering gear. Under these conditions the vessel can be made to turn about on axis somewhere near her middle length without moving ahead or astern. Similarly, helm can be carried with the rudders fully closed, when the vessel turns while going astern.

In order to provide for the power control of the above described maneuvering gear I provide an electric motor 1 which, preferably through reduction gearing, drives the threaded spindle 2, on which is mounted the nut 3, adapted to be displaced by the rotation of said threaded spindle.

Pivoted at the centre of its length to this nut is a yoke 4, and links 5, pivoted at one end to the ends of the yoke 4, are pivoted at their other ends to the arm 6 mounted on the shaft A attached to one deflector blade 11, and arm 8 mounted on a sleeve 7 attached to the other deflector blade 12, by this construction it will be readily seen that the rotation of the motor in the desired direction during a determined period rotates the spindle 2 thereby displacing the nut 3, and, through the yoke 4 and links 6 and 7, opening or closing the blades 11, 12 the desired amount.

It is desirable that means should be provided to ensure that the required setting of the blades is accurately attained when the motor circuit is interrupted.

For this reason automatic means are put in operation to cause very rapid stoppage of the rotation of the motor shaft, and since the spindle is driven from the motor shaft at a considerable reduction in speed, a still more rapid stoppage of the said spindle. This mechanism in the illustrated embodiment of my invention takes the form of a brake having shoes mounted on pivoted arms 13 on opposite sides of a brake drum 14, and normally drawn together by a powerful spring 10, thereby preventing rotation of said drum. Immediately the motor circuit is completed a solenoid is energized and is arranged to draw down one end of a lever 15 which through suitable linkage forces apart the ends of the pivoted arms 13 thus releasing the brake drum; on the motor circuit being interrupted the solenoid is de-energized allowing the spring 10 to again apply the brake.

One convenient method of mounting the controls in the wheel house is shown in Fig. 3 from which it will be seen that three push buttons marked "Ahead" "Astern" and "Reset" are arranged in a small control box mounted on the binnacle.

This control is obviously extremely simple and can readily be operated by the man at the wheel who is thus enabled to control the entire maneuvering of the vessel, a very valuable advantage especially in vessels manned by small crews, such as tugs, barges or small yachts.

It is desirable to provide means to ensure that no injury shall occur to the rudder plates or straining of the actuating mechanism resulting through some obstruction preventing the movement of the blades, and to take care of this contingency an over-load switch is arranged to automatically break the electrical operating circuit when the resistance to movement of the blades becomes undesirably great.

In the power unit shown a switch marked "Reset" is provided on the control board by which the circuit can be re-established after being so interrupted, but this does not set the mechanism in movement until either the "ahead" or "astern" button is depressed, thus by depressing the "ahead" button the blades may be re-opened to release the obstruction and the closing movement then re-commenced by depressing the "astern" button.

Means are preferably provided to prevent the blades being moved beyond a certain maximum setting. In the construction shown in the drawings this is provided for by arranging that the motor circuit is broken when the limiting position is reached by adjustably mounted tripping members 17, 18 on a member 17^a displaced along a threaded spindle rotated during the rotation of the motor 1. In the arrangement shown this spindle 20 is formed as an extension of a shaft 21 driven by the motor through a worm reduction gear. When the contact carrier 17^a has been displaced to the end of its travel one of the contacts 17, 18 carried thereby acts to throw a switch 22 which, as will be seen from the circuit diagram acts to interrupt the circuit of the solenoid 23 holding closed the line switches 24. The opening of these switches stops the motor and automatically applies the brake. Obviously any convenient arrangement of limit switches or stops could be substituted for the particular arrangement just described which is given as an illustrative example and has been used with perfectly satisfactory results in actual practice, and while I have shown by way of illustration a convenient arrangement of electrical control circuit it will of course be understood that my invention is not in any way limited to the precise arrangement of

said circuit as any suitable lay out of the necessary electrical apparatus may be utilized, such a system for instance as that used in electric trains or cars.

The operation of the described and illustrated embodiment of my invention is as follows.

It is presumed that a ship is pulling out of a dock by going astern and for some reason, such as a craft passing across the stern, it is desired to reduce her speed, the push button marked "Ahead" is pressed and kept depressed until the speed falls to that desired. In the "ahead" setting of the switches a path is established for the current drawn from the main line by the auxiliary line branching from the main line at D, the current flowing through the contacts connected by the "reset" control switch in its normal or open position, through the contacts connected by the "ahead" control switch in its operative or closed position, through the contacts connected by the "astern" control switch in its normal or open position, through the energizing solenoid 25 for the main "ahead" control switch thereby closing that switch, and joining the return side of the main line circuit at the main line switch 24.

During the depression of the "ahead" control switch it will be seen that the solenoid S holding off the electromagnetic brake is also energized. On releasing the "ahead" control switch, the circuit just described is interrupted deenergizing the brake solenoid and causing the automatic application of the brake with the result that the rudder plates are held in a position at which they have arrived substantially at the instant of interruption of the power circuit.

It is to be noted that the term "ahead" denotes that the rudder blades are opening into more and more parallel relation to each other; to continue our illustration we will suppose that the ship having been brought from about 4 miles per hour astern to one mile an hour, it is desired to again increase her speed to full astern, the button marked "Astern" is depressed and held depressed. In this "astern" setting of the switches a path is established for the current drawn from the main line by the auxiliary circuit branching therefrom at D, the current passing through the terminals connected by the "reset" control switch in normal or open position to the terminals connected by the "astern" control switch in its depressed or closed position, the terminals connected by the "ahead" control switch in its normal or open position, through the solenoid of the main "astern" control switch 30 thereby closing that switch, and joining the return side of the main operating circuit at line switch 24. While the "astern" control switch is held depressed, the rear edges of the blades

come together until in the normal case they would come into contact, but we will suppose a piece of timber jams between the closing edges and abruptly arrests their movement. The overload switch 27 is thrown, by the heavy rush of current through its solenoid, and the auxiliary circuit through the solenoid 23 holding shut the main line switch 24 is de-energized, the switch being thrown open by the tension spring 24^a, thereby practically instantly stopping the motor by the application of the brake. The overload switch 27 immediately after is brought by any suitable means such as a spring or the weight of its armature, into position to restore the circuit of the main line switch 24 but as this switch is held open by its spring 24^a it is necessary to close the switch marked "Reset" to establish the auxiliary circuit serving to energize the solenoid serving to close the main line switch and hold it closed against the tension of the spring 24^a. In this setting it will be seen that an auxiliary circuit is established branching from the main line at D, current flowing from said main line through the terminals connected by the "reset" control switch in its depressed or closed position through the solenoid holding closed the main line switch against the pull of its retracting spring 24^a, and through the terminals connected by the overload switch in its normal or closed position to the return side of the circuit, the main line switch 24 being maintained closed on the release of the "reset" switch by the feeding of line current drawn from the main line at E and flowing through a local circuit completed by a secondary switch 28 connected to the main line switch so as to be moved into closed position by the closing of the main line switch and through the solenoid of said main line switch, to the return side of the circuit. The rudder plates can now be opened sufficiently to release the obstruction by depressing the switch marked "Ahead" and then the "astern" button can be again depressed, the blades moving together till their edges are in contact when, should the button be still kept depressed, the "astern" limit switch is thrown and the motor stopped, the ship then going full speed astern as long as is desired.

It is believed that the operation of the power control means has been made clear and that it will be seen that a simple and reliable control has been provided capable of being operated by the steersman if desired and therefore enabling all maneuvering of the ship to be effected by one man and without varying the engine speed, these conditions being very desirable in many cases.

While I have described a power control unit which has been found in actual practice of great value and to function perfect-

ly, I do not desire to limit myself to the precise details of construction shown, as various alternative ways of obtaining the features of the control of my invention can be readily conceived by those skilled in the art and I do not therefore desire to limit the scope of the invention except as defined in the appended claims.

I claim:—

1. In ship or boat maneuvering gear of the kind described, an electric motor, rudder blades movable by said motor toward or from each other, means normally tending to cause interruption of the circuit of said motor but adapted to be held out of normal position to enable movement of the rudder blades to be effected, means acting on the release of said control means to immediately interrupt the circuit of the motor, a shaft rotated by said motor, reduction gear transmitting the drive from said shaft to members acting to transmit the drive to the rudder blades and brake means automatically applied on the interruption of the motor circuit to arrest the movement of said shaft.
2. In ship or boat maneuvering gear of the kind described, a source supplying power, rudder blades movable toward or from each other, means operated by power from said source for moving said blades, controlling means whereby the time during which power is applied to the rudder blades is determined, and additional controlling means to cut off said power should an obstruction prevent movement of said blades.
3. In ship or boat maneuvering gear of the kind described, rudder blades movable toward or from each other, an electric motor, means for controlling the circuit of said motor and an overload switch acting to interrupt the motor circuit should the movement of said rudder blades be prevented, the circuit remaining open till again closed by said controlling means.
4. In ship or boat maneuvering gear of the kind described, rudder blades movable toward or from each other, an electric motor, a shaft rotated by said motor and driving a worm, a worm wheel meshing with said worm, a shaft rotated by said worm wheel, and members moved along said shaft by the movement thereof and acting to interrupt the circuit of said motor when the rudder blades have reached their maximum settings in either direction.
5. In ship or boat maneuvering gear of the kind described, an electric motor, and circuit control means for said motor adapted to be arranged in a suitable position adjacent the navigator, said circuit control means comprising a switch for running of the motor in one direction, a second switch for causing running of the motor in the reverse direction, an overload switch, and a third switch whereby the circuit may be reset.

after interruption thereof owing to any cause imposing an overload on said circuit resulting in the opening of the overload switch.

- 5 6. In ship or boat maneuvering gear of the kind described, an electric motor, a shaft rotated by said motor and driving a worm, a worm wheel meshing with said worm, a 10 brake drum mounted on said shaft, a brake shoe engaging with said drum and arranged to be applied automatically on the interruption of the motor circuit, a second shaft driven by a bevel pinion from said worm shaft, means for transmitting the drive from 15 said last mentioned shaft to the threaded spindle of the maneuvering rudder control described, and limiting and overload switch devices adapted to automatically interrupt the motor circuit under certain conditions.
- 20 7. In ship or boat maneuvering gear of the kind described, an electric motor, switch means arranged to control the running thereof in either ahead or astern direction, switch means to automatically interrupt the 25 motor circuit on the rudder blades reaching their limiting positions, switch means automatically to interrupt the motor circuit should the movement of the rudder blades be obstructed and electro-magnetically operated 30 braking means automatically applied by the interruption of the motor circuit to bring the mechanism to a stop.
8. In ship or boat maneuvering gear of the kind described, an electric motor, switch 35 means arranged to control the running thereof in either ahead or astern direction, switch means to automatically interrupt the motor circuit on the rudder blades reaching their limiting positions, switch means automatically to interrupt the motor circuit should the movement of the rudder blades be 40 obstructed, electro-magnetically operated braking means automatically applied by the interruption of the motor circuit to bring

the mechanism to a stop, said braking 45 means comprising a brake shoe member, means tending to force said brake member into engagement with a member driven by said motor and a solenoid normally energized and acting to hold said braking member 50 out of engagement with said driven member and switch means acting automatically to interrupt the energizing circuit of said solenoid when the desired setting of the rudder blades has been attained thus putting 55 the brake into operation.

9. In ship or boat maneuvering gear of the kind described, an electric motor, switch means arranged to normally break the motor circuit so that said motor can be run in 60 either direction for a period determined by the time the requisite switch is held out of normal position, automatically operated means for interrupting the motor circuit when continued application of power to the 65 blades might result in damage, an electro-magnetic brake held out of engagement during the functioning of the mechanism but automatically applied by the interruption of the motor circuit to stop said mechanism, said brake comprising a brake shoe bearing on a brake surface formed on a part 70 rotated during the functioning of the mechanism, said shoe being carried on an arm pivoted at one end to the mechanism mounting, 75 a spring arranged to exert a pressure on the other end of the arm tending to force said shoe into engagement with said bearing surface, and a solenoid energized during the functioning of the mechanism and acting 80 through a lever to hold said brake shoe out of engagement, the de-energization of the solenoid allowing the spring to force the brake shoe into engagement and bring the mechanism to a stop in a very short time. 85

In testimony whereof I have affixed my signature.

ALEXANDER McNAB.
